CLAIM

USPC **D14/142; D14/240**

The ornamental design for an eNodeB, as shown and described.

(58) **Field of Classification Search**

DESCRIPTION

USPC D14/240, 242, 496, 140, 140.1, 140.6,

FIG. 1 is a front perspective view of an eNodeB showing my new design;

D14/142, 230, 299, 125, 129, 130, 155,

FIG. 2 is a front view thereof;

D14/168, 188, 195, 356, 357, 358, 361,

FIG. 3 is a rear view thereof;

D14/362, 365, 367, 370, 388, 432, 434;

FIG. 4 is a left side view thereof;

D13/103, 107, 108, 123, 152, 162, 162.1,

FIG. 5 is a right side view thereof;

D13/163, 168, 184, 199, 137.1, 137.2,

FIG. 6 is a top view thereof;

D13/137.3, 139.1, 158; D10/104.1,

FIG. 7 is a bottom view thereof;

D10/106.1, 106.6, 116.1, 61, 64, 75,

FIG. 8 is a front perspective view of the design of FIGS. 1-7,

D10/106.9; D23/355, 364, 366; D26/26,

shown with an upper module;

D26/72, 73, 32, 34, 366, 367

FIG. 9 is a front perspective view of the design of FIGS. 1-7,

CPC ... H04W 88/08; H04W 88/085; H04W 88/00;

shown with an lower module; and,

H04W 88/005; H04W 88/02; H04W

FIG. 10 is a front perspective view of the design of FIGS.

H04W 88/00; and,

FIG. 1-7, shown with upper and lower modules and wires extending from the rear side of the article.

(Continued)

The broken lines in FIGS. 8, 9, and 10 showing the additional modules and wires depict environmental subject matter only and form no part of the claimed design; while all other broken lines in the drawings depict portions of the eNobeB that form no part of the claim. The unshaded surfaces seen between the solid lines and broken lines form no part of the claim.

1 Claim, 8 Drawing Sheets
